UNITED STATES PATENT OFFICE.

JAMES M. TEAHEN, OF DETROIT, MICHIGAN, AND WILLIAM TAYLOR, OF FORD,
ONTARIO, CANADA; SAID TAYLOR ASSIGNOR TO SAID TEAHEN.

WATER CLOSET.

1,419,328.

Specification of Letters Patent. Patented June 13, 1922.

Application filed June 11, 1920. Serial No. 388,102.

To all whom it may concern:

Be it known that we, JAMES M. TEAHEN, a citizen of the United States of America, residing at Detroit, in the county of Wayne and State of Michigan, and WILLIAM TAYLOR, a subject of the King of Great Britain and Ireland, residing at Ford, in the Province of Ontario and Dominion of Canada, have invented certain new and useful Improvements in Water Closets, of which the following is a specification, reference being had therein to the accompanying drawings:

The invention relates to water closets and has for its object the obtaining of a construction in which the bowl and flushing tank are incorporated in a single integral fixture conforming to the ordinary or extraordinary roughing-in measurements required by plumbing practice.

In the present state of the art the construction of siphon water closet bowls has been reasonably standardized, the ordinary construction thereof being trade styled or named and requiring, as thus known to the trade, certain standardized roughing-in measurements, meaning by this, the distance between the center of the soil pipe or other fitting opening in the floor and the wall in rear of the closet.

There are two types of flushing apparatus in general use, the more common being the gravity system, where the water is supplied to the bowl from the tank or cistern, and the other the pressure system, in which the inflowing water is delivered directly from the water supply into the bowl. As the latter requires a relatively large volume to be discharged directly from the main, it is used chiefly in large buildings provided with their own water supply systems, but the construction in common use is the gravity flush. With this, the tank or cistern is a separate fixture, usually hung upon the wall in rear of the bowl and above the level thereof, being connected thereto by pipe fittings.

It is the object of the present invention to simplify the construction by the substitution of a single unit for the two units required in the gravity flushing system. It is, however, trade important, meaning plumbing practice, to maintain standard dimensions so far as they effect the general accepted roughing-in measurements, and also to obtain a construction which is commercially standard both as to bowl and siphon trap.

It is also important to afford stable support for the tank without the necessity of enlarging the base or pedestal of the fixture or the requirement for any other supporting or stabilizing connection. This result is accomplished by a construction where the tank is integral with the bowl and is stably supported on the same pedestal. The required capacity is obtained either by utilizing the space between the bowl and the rear wall provided by standard roughing-in dimensions or by extending the tank symmetrically upon opposite sides of the pedestal or by a combination of both. The tank is also preferably located in the main between the level of the water seal and the top of the bowl, which permits of a gravity discharge and avoids an objectionable increase in height of the fixture.

In detail and as shown in the drawings:

Figure 1 is a vertical centrally longitudinal section through one construction of the unit;

Figure 2 is a cross-section thereof through the flushing tank;

Figure 3 is a plan view;

Figures 4, 5 and 6 are respectively a side elevation, front elevation and plan of a modified construction.

A is the bowl proper provided with the usual hollow rim B and has its lower end connected with the siphon trap C, including the return-bent portion D and the laterally extending portion E at its lower end, which connects with the nipple F for coupling with the soil pipe. G is the supporting base within which the trap is located. H is the flushing tank, the bottom of which is preferably arranged slightly above the level of the water seal indicated at I, and which extends rearward from the bowl and trap to within a short distance of the roughing-in limit. Laterally the tank is extended on each side of the bowl a distance which will be within roughing-in measurements. There is also provided a connecting channel J between the bottom of the tank and the bowl, the port J' opening into the bowl, being preferably so arranged as to produce a tangential jet movement and also being preferably below the normal level of the water seal.

The construction as thus far described may be used with any suitable construction of flush valve and float-control inlet, these parts being not shown. Also provision may

be made for a rim flush and I have indicated an inlet channel K from the tank to the rim, the upper end of which is above the high level in the tank and the water for this 5 rim flush may be taken directly from the supply, but the mechanism for accomplishing this forms no part of the present invention.

In operation, when the flush valve is actuated to open the port J², which connects 10 the tank with the channel J, the water within the tank will be discharged into the bowl to raise the level therein to an equalizing line, such as indicated at L. This will cause the overflowing of the trap and the forming 15 of a siphon, whereupon the siphonic pressure will produce the rapid discharge of both water in the bowl and the remaining water in the tank. Where the inlet port J² is tangential, the discharge of water there- 20 through will cause a whirling or centrifugal action within the bowl, which will greatly assist in effective flushing.

In the modified construction shown in Figures 4 to 6 the tank is formed by portions H' and H² arranged symmetrically upon opposite sides of the bowl, but not extending in the rear thereof. Such a construction could be placed in locations where the standard roughing-in dimensions have 30 not been complied with and where, therefore, there is not the requisite clearance in the back of the bowl for the construction shown in Figures 1 to 3. The two constructions are, however, the same, in that in each 35 there is a comparatively small head of liquid for effecting the discharge from the tank to the bowl and the velocity is obtained by siphonic action.

What we claim as our invention is:

40 1. A water closet comprising a siphonic action bowl, a tank connected therewith for forming a gravity head between the water seal and the top of the bowl, the normal water level of said tank being located below 45 the top of said bowl, and means for estab-

lishing communication between said tank and bowl to start siphonic action.

2. A water closet comprising a siphonic action bowl, a tank integral therewith for forming a gravity head between the water seal and the top of the bowl, the bottom of said tank being located below the top of said bowl, and means for establishing communication between said tank and bowl to start siphonic action. 50

3. A unit fixture comprising a siphonic action bowl, a tank integral therewith of sufficient capacity for flushing said bowl and arranged above the water seal with its water level below the rim of the bowl, and a pedestal for supporting said tank and bowl. 55

4. A unit fixture comprising a siphonic action bowl, a pedestal for supporting the same, an integral tank above the level of the water seal and in the main below the top of the bowl arranged in the space in rear and at the sides of the bowl provided by roughing-in dimensions. 65

5. A unit fitting comprising a siphonic action bowl, a pedestal for supporting the same, an integral tank projecting rearwardly and laterally from said bowl and partly overlapping the sides thereof, the bottom of the tank being above the water seal, but slightly below the upper end of the siphon which projects centrally upwardly therein. 70

6. The method of flushing siphonic bowl closets consisting in establishing a normal water level above the seal but not greatly above the siphon-forming level in the bowl and in imparting velocity to the water flowing from said tank into the bowl, when in communication therewith, through siphonic action in the bowl. 75

In testimony whereof we affix our signatures. 80

JAMES M. TEAHEN.
WILLIAM TAYLOR.
